INVENTOR.

J. Thomas

ATTORNEY

UNITED STATES PATENT OFFICE.

OWEN L. DAUTRICK, OF DETROIT, MICHIGAN, ASSIGNOR TO THE DAUTRICK COMPANY, OF DETROIT, MICHIGAN, A CORPORATION OF MICHIGAN.

VERTICALLY-SLIDABLE INWARDLY-SWINGING WINDOW.

Application filed April 27, 1925. Serial No. 26,010.

To all whom it may concern:

Be it known that I, OWEN L. DAUTRICK, a citizen of the United States, residing at Detroit, county of Wayne, State of Michigan, have invented a certain new and useful Improvement in Vertically-Slidable Inwardly-Swinging Windows, and declare the following to be a full, clear, and exact description of the same, such as will enable others skilled in the art to which it pertains to make and use the same, reference being had to the accompanying drawings, which form a part of this specification.

My invention relates to an attachment for vertically slidable window sash, whereby the sash may be swung inwardly for cleaning the outer face of the glass and that it may also be inclined and secured rigidly for ventilating purposes, as shown in the accompanying drawings and more particularly described in the following specification and claims.

It is well known that in large offices or apartment buildings the problem of cleaning windows is one involving considerable annual expense due to the time required and hazardous nature of the work.

It is also well known that when vertically movable windows are raised for ventilation that the current of air passing directly through the opening creates a draft which is unpleasant and may cause occupants of the room to suffer from colds.

The primary object of the present invention is to provide an attachment for vertically movable window sash whereby the glass may be quickly and readily cleaned from the inside of the building, thereby greatly reducing the risk incurred by the party cleaning the windows and time required to do the work.

A further object of the invention is to provide means whereby the window sash may be tilted and secured at any desired angle for ventilating purposes in order that air currents may be directed upwardly above the heads of occupants of the room.

A further object of the invention is to provide suitable metallic guides attached to the window casing coordinating with elements carried upon the edge of the sash to facilitate the ready vertical movement of the latter, thus overcoming any tendency to bind and also to insure a close joint between the

window casing and the sash frame to prevent the entry of drafts common to the ordinary wood sash and casing. 55

A further object of the invention is to provide detachable means adapted to be connected with the sash frame and casing to support one of the sash frames in an approximately horizontal position for cleaning and upon which the other sash frame may rest when cleaning the latter. 60

A further object of the invention is to provide means whereby the sash frame may be automatically locked when swung into alignment with the vertically slidable members to which it is pivoted, and which coordinates with the member secured to the window casing. 65 70

A further object of the invention is to provide means whereby the sash may be readily removed from the window casing when required to make repairs—there being no stop bead to remove or replace. 75

With the foregoing and other objects in view which will appear as the description proceeds the invention further resides in the combination and arrangement of parts and in the details of construction hereinafter described and claimed it being understood that changes may be made in the precise embodiment of the invention herein disclosed without departing from the spirit of the same. 80 85

In the drawings accompanying this specification:

Figure 1 is a perspective view showing both sections of the window sash lowered and tilted inwardly in a horizontal position—the lower sash being supported by suitable detachable bracket arms connected with the casing—the upper sash resting on the lower sash frame—the dotted lines indicating the sash frames tilted and secured at an angle for ventilating purposes. 90 95

Figure 2 is a fragmentary perspective view with parts broken away and in section, showing the lower sash frame supported in a horizontal position to a vertically slidable member to which it is pivoted—showing also in dotted lines one of the hooks engaging a pivot pin carried by the vertically slidable member which when disconnected therefrom permits the removal 100 105 of the sash from the window casing.

Figure 3 is an enlarged detail cross-sectional view through the window casing and sash frames taken on or about line 3-3 of Figure 1—the sash however being shown in alignment with the window casing and not as indicated in Figure 1.

Figure 4 is a cross-sectional view through a side bar of the sash frame and member attached thereto, taken on or about line 10 4-4 of Figure 2.

Figure 5 is a similar cross-sectional view taken on or about line 5-5 of Figure 2—showing a fragment of a detachable bar for supporting the sash in a horizontal position.

Figure 6 is a cross-sectional view through one of the sash rails and a fragment of the window casing—taken on or about line 15 6-6 of Figure 2—the sash however being in its normal vertical position, showing a spring latch carried by the vertical slidable member interlocked with the member carried by the sash rail, whereby the sash is maintained in a vertical position.

Figure 7 is a fragmentary elevation of the 25 vertically slidable element supported in the window casing and the swinging element detachably pivoted to the vertically slidable element by a swinging latch hook carried by the swinging element engaging a pin 30 projecting from the vertically slidable element—the latch hook being raised—as when removing the sash—not shown—the view also shows a fragment of a detachable bar for supporting the sash in a horizontal position—the parts attached to the sash being raised to free it from a weather-strip secured to the sill that the sash frame may be 35 swung horizontally for cleaning the glass.

Referring now to the letters of reference 40 placed upon the drawings:

A denotes a sash frame—to the side members of which are secured L-shaped sheet metal strips B spaced from the edge of the frame by a relatively narrow interlaying strip C, thereby providing a groove C^a at 45 one side of the sash rail. B^b indicates screws for securing the L-shaped and interlaying strip to the sash rail.

D designates the stile of a window casing 50 to which is nailed or otherwise secured an L-shaped strip E—its outer projecting edge E¹ extending between return bends of a vertically slidable sheet metal member F, of channel-like form. One of the channel walls of the member F is provided with an L-shaped return bend with one of its flanges f spaced from the back of the channel that 55 it may slide in the groove C^a, between the L-shaped member B and the edge of the sash rail.

G denotes a flat spring secured by a grommet g to the channel member F, fitted with a wedge-shaped detent G^a, designed to enter 60 a slot B^a in the L-shaped strip B, thereby 65 detachably engaging the latter to the channel

member. To provide for readily detaching the channel member F from locked relation with the L-shaped member B, the channel member is cut-away at f—see Figure 2—to expose the projecting end G¹ of the 70 spring that it may be forced back by applying a suitable instrument—thereby withdrawing the detent G^a from the slot B^a, in the member B attached to the sash.

H denotes a plate provided with a sash 75 cord hook H¹ at its upper end secured to the inner wall of the channel member F at h, h, by grommets or eyelets, thus providing at its upper end an aperture to receive the studs of a supporting bar I, engaged at its lower end with the sash, through an opening provided in the L-shaped member B.

The bars I, are designed to support the sash frame in an inwardly directed horizontal position, whereby the outer face of the glass may be readily cleaned from the inside of a room.

Secured to the hook H¹ at the upper end 80 of the plate H, is the usual sash cord J, in turn attached to the usual sash weight—not shown—for counterbalancing the window.

K denotes a spring actuated hook which 85 is adapted to engage screws L projecting from the stiles D of the window casing into the pockets formed by the channel members—the purpose being to lock the vertically slidable members F and B against the 90 lifting action of the sash weights when the sash is swung into a horizontal position—as indicated in Figure 2—for cleaning.

Carried by the spring latch K and projecting through an arc-shaped slot in the channel member F is a pin K^a which is 95 adapted to be acted upon by the end wall of a slotted recess B^b formed in the L-shaped strips B—the strip upon contacting with the pin K^a serves to force the latch K out of locking relation with the screw L 100 when the sash is returned to its normal vertical position in alignment with the channel members F.

Pivoted to the L-shaped members B at the lower end of the sash are swinging 105 hooks M adapted to engage a pin F^a projecting from the wall of the channel member at its lower end. By releasing the hooks M and detaching the supporting bars I, the sash may be readily removed from 110 the window casing for repairs, without the necessity of removing or replacing the usual "stop beads".

N denotes an upwardly projecting sheet 115 metal weather strip secured to the sill adapted to enter a slot—not shown—provided in the lower edge of the sash and corresponding with the slot F^b at the lower 120 end of the channel member.

When it is desired to swing the sash into 125

a horizontal position as shown in Figure 2, the sash must be raised sufficiently to clear the weather strip N before swinging it into the position shown.

B^c designates holes punched through the upper ends of the strips B—which in conjunction with the aperture formed by the grommets g, connecting the spring latch with the channel member F—are designed to receive studs projecting from each end of a relatively short pair of supporting bars P, to maintain the sash at an angle for ventilating purposes—as indicated in dotted lines in Figure 1.

15 It will be understood that the coordinating members of the upper sash are similar to those of the lower sash, and it is not considered necessary to duplicate either the drawings or description of same to convey 20 a complete understanding of the invention.

Having now indicated the several parts by reference letters the construction and operation of the device will be readily understood.

25 The sash when in normal position is in alignment with the vertically slidable channel members F, and is secured thereto by the spring latches G, carried by the channel member F entering the slots B^a in the 30 L-shaped strips B, secured to the edges of the sash.

When it is desired to swing the sash into a horizontal position—as indicated in Figure 2—for cleaning the outer surface of the glass, the spring latches are released by pressure upon the upper ends of the springs G. The sash is then swung inwardly to the position shown, whereupon the latches K—due to the action of their 40 springs—engage the screws L, projecting from the window casings into the space provided between the walls of the channel members. The channel members F are thus held against upward movement due 45 to action of the counterweights.

The supporting bars I, with their projecting studs at each end, are now engaged through the apertures provided in the respective channel members F, and L-shaped bars B, secured to the edges of the window sash.

To clean the outer face of the upper sash, the latter is lowered and swung inwardly, the respective latches K of the upper sash engaging screws L, as in the case of the lower sash. The upper sash however rests directly upon the lower sash, as indicated in Figure 1, without the use of additional supporting bars I.

If it is necessary to remove the sash from the vertically slidable channel members F for repairs or other purposes, the swinging hooks M carried by the bars B at the lower edge of the sash are raised to release the pins F^a, carried by the channel members F.

The sash may then be removed from the window casing.

Upon returning the sash to its normal vertical position the supporting bars I, I, are first removed and the sash swung into alignment with the channel members—the end wall of the recess B^a in the L-shaped strips B forcing the pins K^a of the spring controlled latches K out of engagement with the screws L—the spring latches G simultaneously entering the slot B^b in the strips B, thereby automatically locking the sash in vertical alignment with the channel members F.

If it is desired to tilt the windows at an angle for ventilating purposes a pair of relatively short supporting bars P fitted at each end with studs are employed to connect the upper ends of the sash with the channel member by inserting the studs in the respective apertures provided to receive them—the sash is thus supported at an angle so as to direct the air currents upwardly to avoid drafts.

It will be apparent that the angle or L-shaped strips E, secured to the stile of the window casing serves not only as a guide for the channel members F but insures a tight joint between the parts.

Having thus described my invention what I claim is:

1. In a device of the class described, a pair of vertically movable channel members provided with horizontally projecting pivot studs, a vertically slidable sash provided with metal strips secured to the sash and having bearing recesses receiving the pivot studs and a pair of swinging hooks provided with recesses intersecting the recesses of the said strips and receiving the pivot studs for confining the said pivot studs in the recesses of the said strips.

2. In a device of the class described, a pair of vertically movable channel strips provided adjacent their lower ends with horizontally projecting head studs, a vertically movable sash provided at its side edges with sheet metal strips extending longitudinally of the sash and provided at their lower ends with vertical recesses extending upwardly from the lower edges of the said strips and receiving the said studs, a pair of laterally swinging hooks pivoted to the sash and provided with recesses arranged to intersect the recesses of the said strips and receiving the studs to confine the latter in the said recesses.

3. In a device of the class described, a pair of vertically movable channel members, a sash pivoted to the channel members and adapted to swing inwardly therefrom and means for automatically locking the channel members against upward movement when the sash is swung inwardly, said means comprising a horizontal pin fixed with relation

to the vertically movable members and a spring actuated catch arranged vertically and pivoted at its upper end and having its lower end beveled and provided with a recess 5 for engaging the said fixed pin, and a projection carried by the catch and extending into the path of the sash and arranged to be engaged by the same whereby the catch is disengaged from the pin when the sash is returned to its normal vertical position. 10 In testimony whereof, I sign this specification.

OWEN L. DAUTRICK.
